(57) **CLAIM**

The ornamental design for a breast pump bag with pockets, as shown and described.

DESCRIPTION

FIG. 1 is a front perspective view of a breast pump bag with pockets showing our new design;

FIG. 2 is a front elevational view thereof;

FIG. 3 is a rear elevation view thereof;

FIG. 4 is a right-side view thereof;

FIG. 5 is a left-side view thereof;

FIG. 6 is a top plan view in a closed configuration;

FIG. 7 is a bottom plan view thereof; and,

FIG. 8 is a top plan view of an alternative configuration in an opened position.

The broken lines depict portions of the article that form no part of the claimed design.

Mesh pockets are shown on the right and left sides of the bag.

1 Claim, 8 Drawing Sheets
